UNITED STATES PATENT OFFICE.

GEORGE HENRY GIDDINGS, OF ILION, NEW YORK.

BREECH-LOADING FIREARM.

1,156,222.

Specification of Letters Patent.

Patented Oct. 12, 1915.

Application filed March 2, 1914. Serial No. 821,947.

To all whom it may concern:

Be it known that I, GEORGE H. GIDDINGS, a citizen of the United States, residing at Ilion, in the county of Herkimer and State 5 of New York, have invented a new and useful Improvement in Breech-Loading Firearms, of which the following is a specification.

My invention relates generally to breech 10 loading fire arms and has for its object to provide a simple, effective and reasonably cheap lock mechanism for such guns.

My improvements relate particularly to the cocking mechanism in connection with 15 a novel construction of safety mechanism, and the construction and arrangement of these parts are such as to permit the arrangement of a novel construction of barrel locking mechanism, all of these various combinations being arranged in that type of arm 20 in which removable lock plates are secured to opposite sides of the breech frame.

With these various objects in view, and with certain other objects as will hereinafter 25 appear my invention consists in the various novel features of construction, combination and arrangement all of which will be fully described hereinafter and pointed out in the claims.

30 In the drawings forming a part of this specification: Figure 1 is a side view of a gun frame and a portion of the barrel joined to said frame, one lock plate being removed, and a portion of the frame indicated in section. Fig. 2 is a similar view showing the barrel broken down and the hammers nearly cocked. Fig. 3 is a similar view showing the hammers at full cock and the safety indicator at the point indicating safety. Fig. 4 35 is a transverse sectional view taken on the line 4—4 of Fig. 2, and Fig. 5 is a similar view taken on the line 5—5 of Fig. 1. Fig. 6 is a view showing side and end views of a bolt or check used in connection with the 40 barrel locking bolt. Figs. 7 and 8 are views illustrating the manner of disconnecting the barrel from the frame and also illustrating the means for operating the cocking lever. Fig. 9 is a view showing side and edge views 45 of one of the lock plates with the parts connected thereto. Fig. 10 is a view showing the side and end views of a cocking lever, and Fig. 11 is a bottom plan view of the 50 barrel locking bolt and the rod attached thereto for carrying the spring.

In the practical embodiment of my invention I employ a gun frame 10 and barrels 11, the barrels having a depending lug 11^a which fits between the fork end of the frame and turns upon the joint pin 12, a fore-end 60 iron 13 being used in connection with the barrels and frame to complete the assemblage of these parts.

It is preferred to arrange the hammers 14 having the main springs 15 connected thereto, the sears 16 and the sear springs 17 bearing thereon, mounted upon the side plates 18, these side plates being removably secured to the opposite sides of the frame 10. The rear ends of the sears are formed with lateral extensions 16^a which extend immediately over the triggers 19 and 20 as most clearly shown in the drawings.

The cocking of the gun when the barrels are broken down is accomplished through a 75 hook 21 pivoted at 21^a in the slotted portion of the barrel lug 11^a, the hook 21 co-acting with the hooked end 22^a of the cocking lever 22, said cocking lever being pivoted within the frame. As before stated the hook 21 80 is pivoted at 21^a, the pivot being adjacent the upper end of the hook and a spring 24 tends to throw the hook 21 down to the position shown in Figs. 7 and 8, so that the barrel can be disconnected from the stock 85 when desired. This spring 24 is counteracted by a plunger rod 23 which is loosely mounted in the barrel lug and is caused to bear against the hook 21 by the abutting face of the fore-end iron 13 when the parts are 90 assembled, as most clearly shown in Figs. 1 and 2, and when the iron 13 is in contact with the plunger rod 23 said plunger rod will hold the hook 21 in engagement with the hooked end 22^a of the cocking lever 22, 95 so that when the barrels are broken and thrown to the positions shown in Figs. 2 and 3 the cocking lever will be raised at its forward end and turned upon its pivot so as to throw the trunnions or fingers 22^b rearwardly, these trunnions or fingers operating upon the hammers to force them back to a cocked position, Fig. 2 indicating the partially cocked position and Fig. 3 the completely cocked position.

100 It will thus be seen that I provide a simple and efficient construction carried by the barrel which will coact with the cocking lever for the purpose of cocking the hammers and which mechanism can be rendered 105 110

easily ineffective and readily detachable with the barrel by simply removing the fore-end iron.

In order to lock the barrel when in a closed position I provide the barrels with a lump or extension 25 which is slotted at 25^a to receive a laterally swinging bolt 26 operated by the top lever 27 through the medium of a pivot post 27^a, and a spring 28 which surrounds a rod 28^a pivotally connected to the rear end of the bolt 26 as most clearly shown in Figs. 1, 2, 3, and 11. The spring normally holds the bolt in its operative or closed position, the bolt entering the notch 25^a when the barrels are closed as shown in Fig. 1 and when it is desired to break the barrels the top lever 27 is shifted to one side compressing the spring 28 and rocking the bolt 26 so as to withdraw the same from the notch 25^a and the barrels can then be thrown down to the position shown in Fig. 3 for the purpose of recocking the gun and also permitting the unloading and reloading of the gun.

For the purpose of locking the bolt 26 temporarily in its open position, or in other words the position shown in Figs. 2, 3 and 4 I employ a supplemental bolt or check 29, which is mounted to slide vertically upward in the breech frame and is located just below the bolt 26 as most clearly shown in Figs. 4 and 5. This supplemental bolt or check is illustrated in detail in Fig. 6, and from which it will be noted that it is provided with webs or fins 29^a and 29^b which fit in corresponding slots in the breech frame and thereby prevent rotation of the check and guide the same in its movements. The web 29^a is extended upwardly beyond the face of the bolt 29 as shown in Figs. 4 and 6, this extended fin or web being adapted to enter behind the edge of the bolt 26 or engage a notch in said bolt 26 as shown in Fig. 4 thereby locking said bolt 26 against any return movement, and a spring 30 held in place by a pin 30^a normally projects the supplemental bolt or check upwardly the moment the bolt 26 is thrown to one side by the lever 27 and the lump or extension 25 withdrawn from the recess 10^a produced in the frame. When the end of the barrel is thrown into a closed position as shown in Fig. 1 the lower end of the lump or extension 25 engages the supplemental bolt or check 29 and forces the same down to the position shown in Fig. 5 and the spring 28 acting upon the bolt 26 immediately throws it into engagement with the notch 25^a so that the barrel is locked to the frame and the lever 27 will occupy its normal or central position.

Having now described the manner of connecting the barrel and frame, and co-acting parts for cocking the hammers and also the means for locking and unlocking the barrel

I will now describe the safety device which I employ in connection with the lock mechanism to render the same perfectly safe, and in carrying out my invention in this particular I employ a spring bar 31 which is mounted to slide on the under side of the top of the frame 10, this spring bar 31 having a depending arm 31^a which is adapted to engage the lateral extensions 16^a of the sears 16 as more fully explained hereinafter. 75

At its rear end the bar 31 carries a roller 32 which is adapted to engage either one of the two notches 33 and 34 cut in the under side of the top of the frame as most clearly shown in Figs. 1, 2 and 3, the notch 34 being 80 preferably of greater length than the notch 33. A fixed post 10^c is arranged within the frame 10 and has a push rod 35 slidably mounted therein, this push rod occupying a position between the cocking lever 22 and the depending safety arm 31^a, the length of this push rod being such, that when the cocking lever is forcing the hammers to full cock the said rod will operate and force the arm 31^a rearwardly sufficient to move the 90 rear end of the arm 31 with its roller 32 from the notch 33 into the notch 34 as shown in Fig. 2, and in the meantime the safety arm 31^a is prevented from completing its rearward movement by the sear extensions 16^a which block its way as is also shown in Fig. 2, the forward ends of the sears being depressed and their rear ends elevated until the hammers reach full cock and when they do reach full cock the forward ends of the sears engage the hammer notches and their rear ends then drop to the position shown in Fig. 3 and the safety arm 31^a is allowed to complete its rearward movement. The safety arm 31^a then lies immediately over the sears and the fire arm 95 cannot possibly be discharged until the safety arm is moved forward, and this is accomplished through the thumb piece 36 mounted on the upper side of the frame 10 100 and connected to the sliding arm 31. 105

The movement of the safety arm 31^a from a position shown in Fig. 2 is performed by the roller 32 co-acting with the inclined wall of the notch 34, so soon as the sear nose 115 moves into the hammer notch and thus allowing the rear end of the sear to drop to a position below the end of the arm 31^a.

It will thus be seen that I provide a simple durable and efficient fire arm mechanism 120 capable of accomplishing the objects hereinbefore referred to.

What I claim is:—

1. In break down gun, the combination with a barrel and frame, of a spring actuated hook carried by said barrel, a hammer and sear and safety arm carried by the frame, a push rod adapted to operate upon said safety arm and a cocking lever adapted to be engaged by the barrel hook and oper- 125 130

ate upon the hammer and push rod as set forth.

2. In a break down gun, the combination with a hammer and spring of a sear and spring, a safety rod slidably mounted on the gun frame and having a post adapted to co-act with the sear, a push rod for engaging said post and a cocking lever adapted to operate upon the hammer and push rod.

10 3. In a break-down gun, in combination, a hammer, a hammer spring, a sear, a sear spring, a cocking lever, a safety rod slidably mounted on the gun frame, said safety rod being formed with a post adapted to co-act 15 with the sear and with a spring arm terminating with an idle roll, a notch in the frame to receive said roll, and a second notch in said frame with an inclined wall to automatically move the said spring arm and the 20 connected post to their operative or "safe" positions.

4. In a break-down gun, in combination, a removable side-plate, a hammer and a sear mounted on said side plate, a cocking lever 25 pivotally mounted in the frame, a cocking lever hook hung in the barrel lug, and means consisting of a push-rod and co-acting fore-end iron for retaining the said hook in operative relation to the cocking lever.

30 5. In a break-down gun, the combination with the barrels having a barrel lug, a hook pivoted therein, spring actuated in one direction, a plunger rod adapted to counter-act the effect of said spring, a fore-end iron 35 adapted to contact with said plunger rod and hold the same in engagement with the hook, of a cocking lever adapted to engage

at its forward end the hook and barrel lug, the rear end of said cocking lever being adapted to operate upon hammers, a push 40 rod adapted to be operated upon also by said cocking lever, a safety arm adapted to be engaged by the rear end of said push rod, said safety arm being adapted to co-act with sears co-operating with the hammers as set 45 forth.

6. In a break-down gun of the kind described, the combination with the barrels and frame, said barrels having a slotted rear extension, a spring actuated bolt arranged 50 within the frame and operatively connected with a shifting lever, a spring actuated check arranged beneath said bolt and adapted to engage the same in an opened position, a slotted lug connected also to the barrel, a 55 hook pivoted therein spring pressed in one direction and plunger pushed in the opposite direction, a cocking lever arranged within the case and adapted to engage at its forward end with the pivoted hook in the barrel lug, hammers adapted to be engaged by the rear end of said cocking lever, sears and springs operatively connected with said hammers, a push rod adapted for contact with the rear end of the cocking lever, a 60 safety arm adapted to engage the sears and to be engaged by the rear end of said push rod together with a thumb piece for moving said safety arm all arranged and adapted to operate substantially as described.
